FRANK E. WINSTON AND VICTOR B. ROGERS, OF NEW YORK, N. Y.

CUFF-LINK.

1,227,864.

Specification of Letters Patent. Patented May 29, 1917.

Application filed April 29, 1916. Serial No. 94,288.

To all whom it may concern:

Be it known that we, FRANK E. WINSTON and VICTOR B. ROGERS, citizens of the United States, and residents of New York city, in the county of New York and State of New York, have invented certain new and useful Improvements in Cuff-Links, of which the following is a specification.

Our present invention relates to cuff links of the class now commonly used for men's shirts, the cuffs of which are customarily bent at the middle so as to bring the free ends approximately parallel with the two button holes opposite each other. 10 The links comprise two heads and an intermediate shank, the shank being of suitable length and the heads at a suitable angle for permitting opening up of the parallel faces of the cuff to permit insertion of the hand. 15

We have utilized these features of prior construction which permit convenient diverging of the parallel sides of the cuff, retaining all of the advantages of the former rigid construction, and in addition we have 20 made the shank extensible without sacrifice of rigidity, so that our link permits not only ready insertion of the hand, but in addition the drawing of the cuff far up on the arm without the necessity of unbuttoning either of the links from its button-hole. 25

The further features and objects of our invention will be more fully evident from the detailed description thereof in connection with the accompanying drawings, in 30 which—

Figure 1 is a side elevation of the cuff link,

Fig. 2 is a longitudinal section of the link in its extended position,

Fig. 3 is a transverse section through the shank on the line 3—3 of Fig. 1, and

Fig. 4 is a similar section on the line 4—4 of Fig. 2.

The link is provided with heads which 45 may be of any desired construction but are preferably formed of the flat plates 1 and 2 rigidly secured to the shank at 3 and 4 respectively. Cover plates 5 and 6, plain or ornamented may be secured over the 50 base plates in any suitable way as, for instance, by bending or spinning inturned flanges as at 7 and 8. The shank comprises a tubular section 9 telescoping within a corresponding section 10.

By reference to Fig. 3, it will be seen

that the tubular sections are of flattened cross-section, the greatest diameter being disposed transversely to the length of the elongated head 2, so the shank fits flatwise in the button-hole while the head remains 60 crosswise thereof. Thus the flattened shank coöperates with the elongated head in holding the flat surfaces of both heads parallel with the diverging sides of the cuff when in position on the wearer. Furthermore 65 the flattening of the shank prevents relative rotation of the head 2 with respect to the head 1. Thus the latter which is round is also held parallel with the adjacent surfaces of its end of the cuff. 70

The shank section 10 is formed with opposite longitudinal ribs 11 and 12 affording internal guideways or slots 13 and 14 in which are engaging lugs 15 and 16 formed on the end of the shank section 9. The material of the ribs is bent in at the ends 17 and 18 so as to prevent withdrawal of the lugs and disengagement of the sections. 75

Within the telescoping shank section is a spring 19 having one end secured to the 80 head 1 and the other end to the head 2, preferably by extending the end of the spring through a central perforation in the head and bending the material of the spring to prevent its withdrawal. 85

The above described device can be easily and cheaply made. The shank sections 9 and 10 can be made in long tubes either by drawing process or by welding or soldering sheet metal. The base plates 1 and 2 may 90 be stamped and perforated by one stroke of a suitable punch. The tube lengths may then be brazed or soldered to their respective plates. The spring may be then inserted and the ends bent over. The cover plates 5 and 6 may be then applied and the flanges 7 and 8 inturned to secure them to the base plates and if desired, they may be arranged to pinch the ends of the spring to prevent withdrawal thereof. The ends 17 and 18 95 of the ribs 12 and 13 are then inturned to prevent withdrawal of the lugs 15 and 16, thus completing the article. 100

In use, the completed article has all the advantages of the present cuff link; the shank is rigid as before; the heads are non-rotatable with respect to each other as before; the normal size and use of the link is in all respects the same as before; and yet, when the wearer desires to pull up his shirt 110

5 sleeve from the wrist to the forearm, the shank of the button will automatically lengthen out to twice its former length without danger of catching or pulling the flesh or hair of the forearm. When the cuff is pulled down again, the link automatically contracts to its former length.

10 While we have thus shown and described with considerable particularity a desirable embodiment of our invention, it will be obvious that the same features may be embodied in specifically different constructions without departure from the spirit of our invention.

15 We claim:

1. A cuff button composed of heads, a hollow shank connected at one end to one head and formed with opposite outwardly extending longitudinal ribs which latter are 20 formed hollow and open into the interior of the shank, a hollow shank connected to the other head and received within the first named shank, lugs on the inner end of the second named shank sliding within the rib 25 interiors, and a spring connecting the heads, and extending through the shanks, the inner end of the first named shank being curved inwardly to engage the lugs s as

30 to restrict the extent of separating movement between the heads.

2. An extensible cuff button composed of heads, a rigid hollow shank connected at one end to one head, a rigid hollow shank connected at one end to the other head, said shanks being telescoped for free sliding 35 movement, means between the shanks to restrict the separating movement thereof, and a contractile spring within the shanks connected at its ends to the respective heads.

3. A cuff button composed of rigid telescopic shanks, a head secured to the outer end of each shank, one of the shanks being engageable with the head of the other shank to restrict the extent of approaching movement of the heads, means to prevent relative rotation between the shanks, means to prevent relative separation of the shanks, and a contractile spring connected at its 40 ends to the heads to normally hold said one shank and head of the other shank engaged. 45 50

Signed at New York city, in the county of New York and State of New York, this 28th day of April, 1916.

FRANK E. WINSTON.
VICTOR B. ROGERS.
